THE NATIONAL LIBRARY OF AUSTRIA, VIENNA

1. 132-2951.

Application filed Aug. 1, 1926. Serial No. 778,691.

To all whom it may concern:

Be it known that I, Ivan B. Watson, a citizen of the United States, residing at Syracuse, in the county of Onondaga, State of New York, have invented certain new and useful Improvements in Can-Shortening Machines, of which the following is a description, reference being had to the accompanying drawing, and to the Figures of reference marked thereto.

The invention relates to new and useful improvements in can closing machines, and more especially to machines of this type, for attaching a can end or cover to a closed can.

15 body. An object of the invention is to provide a mechanism automatically actuated by the mechanism for placing a end or cover depending roll on the end or cover 20 and the end or cover will be seated on the roll and just prior to the engagement of the can body and end or cover with the sealing rolls.

25 A further object of the invention is to provide a device of the above character with mechanism whereby the device, for sealing the can ends, are rendered ineffective when there is no can body for dictating all the sealing head.

30 These and other objects will in part be
obvious, and will in part be therefore
more fully disclosed.

In the drawings, which show by way of illustration one embodiment of the invention, Figure 1 is a side elevation of a closing machine embodying my invention; Fig. 2 is a front view of a portion of the same; Fig. 3 is a vertical sectional view through the sealing heads and the stack 35 for the can ends; Fig. 4 is a detail in perspective showing the paddle for placing the can ends under each the heads; Fig. 5 is a detail in side elevation of the member for feeding the can ends; showing the parts in 40operative or indirect position; Fig. 6 is a similar view showing the member for operating the piston at the other end of its stroke; Fig. 7 is a detail in plan showing the supporting bracket for the can ends and 45 the devices for feeding the can ends; Fig. 50 the

8 is a view similar to Fig. 5 showing the controlling rates of ice caused by a filled can and the rate required for effective operation.

The invention consists generally in providing a stock holder for the covers or can 55 ends which is so connected with the seatings 60 and 65 as to be raised and lowered thereby, a pusher is used for engaging the lower end of cover in the stock and for delivering the same underneath the seating 60 bearing 61 on a supporting plate where the end of cover is held until engaged by the fixed part. In order to prevent the striking of can ends or covers underneath the head when there is no can to 65 be closed, the reciprocating member for the pusher is so connected to an oscillating lever 70 that it may be torqued from the vertical, the reciprocations of the slide 75 member. This coupling and uncoupling of 70 the slide to the oscillating lever is brought about by the slide arms themselves as they are fed into the closing machine.

Referring more in detail to the drawings, the first closing machine consists of a frame 75 upon which is mounted a seaming head 2. This seaming head consists of an inner and outer sleeve, and on the outer sleeve are mounted levers 3, 3 carrying seaming rolls 4, 4. The inner sleeve is provided with 80 stops 5 for supporting the levers when one sleeve is moved relative to the other. Centrally of the sleeve is a chuck 6, and centrally of the chuck is a setting pad 7. The seaming head 2 is carried by a sleeve 8, 85 which carries a setting pad 7 is carried by a stem 9. The seaming head is moved up and down by a lever 10, and said seaming head is rotated through a gear 11, which meshes with a gear 12 carried by a shaft which is 90 driven by a belt 13. The setting pad stem is moved up and down by a lever 14, which is rotated by a cam actuated by a shaft, the axis of which is indicated at 15. This shaft is driven by a gear 16, which meshes with a second gear in the cross shaft carrying the gear 12. The lever 14 is also actuated by a cam on this shaft, which is operated by a gear 16.

The fixed cash are fixed on a permanent basis.

17 in any suitable way, and are caused to slide along the support by a drum 18 having a spiral thread 19 thereon. This thread is so constructed that when a filled can body 5 reaches the position indicated at 20 in Fig. 2, it is given a slight dwell, after which it is moved bodily forward to the position indicated at 21 in said figure where it is closed. Moving up and down with the 10 seaming head is a supporting plate 22. This supporting plate 22 has a tapered opening 23 and a seat 24 for the can end or cover. When the supporting plate and seaming head are lowered, as viewed in Fig. 3, the 15 cover is brought into contact with the filled can body indicated at 21 in this figure. The cover is seated thereon, the chuck then engages the cover, and the can body is held from movement while the plate 22 is lowered to permit the action of the seaming rolls 4, 4, which are then caused to contact with the can end or cover and the flange of the can body, and roll the same into a double seam.

25 The can ends or covers indicated at 25 in Fig. 3 are carried by a stack holder which is mounted on the supporting plate 22, and said stack holder includes rods 26, which hold the can covers in place. The plate 22 is provided with a groove or recess 27, along which the can ends or covers may slide on to the seat 24. The can ends are removed from the stack by taking the same, one at a time, from the lower end of the stack. In 30 order to accomplish this I have provided a pusher 28, which slides underneath the stack holder, along the inner recess 29 formed in the plate 22. This pusher at its forward end is provided with a separating lip 30. As the pusher is moved forward the separating lip 30 will pass between the two lower can ends or covers and the end 31 of the pusher will engage the lower can end or cover and force the same along the recess 35 27. The stack will rest on the slide 28 until the same is withdrawn when it will drop to a position so that the next can end or cover may be detached from the stack and delivered to the seaming head.

40 The pusher 28 is reciprocated by a bracket arm 32, which extends at an angle to the pusher and is provided with a sleeve 33 adapted to engage the end of a slide rod 34. Nuts 35 and 36 are threaded on the slide rod 45 and provide for a limited adjustment of the bracket arm 32 relative to the slide rod. The supporting plate 22 is fixedly mounted on rods 37, which are adapted to reciprocate in bearings 38 carried by the frame of the 50 machine, and also bearings 39 carried by the frame of the machine, which are disposed so as to engage the upper ends of the rods. The brackets in which the bearings 38 and 39 are located also form bearings for the sleeve for the rotating seaming head. 65 The sleeve for the seaming head, as above noted, is moved up and down by a lever 10. This lever at its outer end is yoke shaped and engages a collar 40, which is mounted on the sleeve for the seaming head, 70 and is held from longitudinal movement thereon. A cross head 41 is also attached to this collar and moves up and down with the seaming head. The rods 37 pass through the cross head 41. These rods are 75 formed with shoulders against which the against the cross head and hold the same on the upper portion of the rods bear against the cross head and holds the same in fixed relation to the rods 37. These rods 80 above the nuts 42 are reduced in diameter so as to permit the placing of the nuts thereon and the reduced parts 37^a slide in the bearings 39. From the above construction it will be apparent that the supporting plate 85 22 will be moved up and down in unison with the seaming head.

86 The supporting plate 22 is provided with bearings 43 and 44, in which the slide rod 34 reciprocates back and forth, the pusher 28 which is rigidly attached thereto, will also move back and forth carrying the ends or covers one after another underneath the seaming head. Mounted on the slide rod 34 so as to 90 move freely thereon is a sleeve 45. This sleeve 45 is pivoted to an arm 46 by a pivot pin 47. The arm 46 slides freely in a lever 48, which is pivoted at 49 to the frame 1 of the machine. The upper end of the lever 100 is formed with a slot 50. A crank pin 51 carried by a disk 52 bolted on the end of a cross shaft, actuated by the gear 16 engages freely in the slot 50 and as the disk rotates, the lever 48 will oscillate about its fulcrum 105 point 49. This oscillation of the lever 48 will cause the sleeve to slide back and forth freely on the slide rod, except at times when the sleeve is coupled to the slide rod and then the slide rod will be moved back and 110 forth with the oscillations of the lever 48. The sleeve moves in a straight line and the arm 47 slides lengthwise in the lever 48 to permit this movement. The slide rod 34 is provided with a collar 53, which is formed 115 with a locking lip 54. Mounted on the sleeve 45 is a latch 55, having a nose 56, which is adapted to lock behind the lip 54 on the collar 53. This latch 55 is mounted in a groove in the sleeve 45, and is held 120 pressed into locking engagement with the lip by a spring 57. The outer end of the face of the collar leading to the lip 54 is beveled as at 58 and the forward edge of the nose 56 is also beveled so that when the 125 latch is in the position shown in Fig. 6, it will automatically engage the lip on the collar 53, provided said lip is free to engage

therewith. When the latch is locked to the collar 53, then the sleeve is fixedly attached to the slide rod, so that the slide rod will move back and forth as the lever oscillates.

5 As a means for controlling the engagement of the latch with the collar I have provided a controlling mechanism which consists of a plate 59 which is carried by a plunger 60, mounted to slide vertically in a bearing 61 of the bracket support for the plate 22. A spring 62 normally forces the plate 59 downwardly and a collar 63 limits the downward movement thereof. Said plate is formed with guiding shoulders 64 and 65, which engage the side faces of the bearings 44 and 43. This prevents any turning of the plate about the axis of the plunger 60. This plate, at the left hand end, as viewed in Fig. 8, is provided with a releasing cam 65. This cam, when the plate is in its lowered position, as shown in Fig. 5, is so positioned as to engage a pin 66 carried by the latch 55, and move the same so as to prevent its locking with the lip on the collar 53. When, however, the plate 59 is raised as shown in Fig. 8 of the drawings, then the latch is free to lock with the lip on the collar 53. The plate 59 being supported by the bracket which carries the plate 22, will move up and down with the seaming head. As clearly shown in Fig. 2, this plate 59 is positioned so as to be directly over the filled can in position 20 as the filled can descends before it is carried forward into the closing machine. In other words, when the seaming head is lowered for closing the can at position 21, the can at position 20 will engage the plate 59 and raise the same, compressing the spring 62.

40 Let us suppose that there are no cans in the machine, and a can is placed on the drum and carried forward to the closing machine. When the filled can reaches the position indicated at 20 it is given a slight dwell by reason of the shaping of the thread 19 on the drum, and in this position the seaming head as it descends will move the plate 59 in contact with this can at position 20, thus lifting the cam 65 so as to allow the latch 55 to engage the lip on the collar 53, and as the lever 48 returns, the slide rod 34 will be carried along therewith, and the pusher 28 moved so as to convey a can end or cover on to the seat beneath the seaming head ready for the filled can when the head rises and the can is moved underneath the same for the next seaming operation. If no other cans are placed in the conveyor during the next downward stroke of the seaming head, the plate 59 will remain in its lowered position so that the cam 65 will hold the latch 55 from locking with the collar on the slide rod 34, and, therefore, the sleeve 45 will slide idly on the rod 34. In other words, it will

be apparent that I have provided a mechanism for feeding the can ends or covers underneath the seaming head which is so controlled by the filled cans as they are fed to the closing machine, that a can end or cover is delivered only as the filled cans are presented to the seaming head, one cover or can end for each filled can, and each can end or cover is presented to the seaming head in proper timing for the closing operation. While the can ends or covers are fed mechanically to the seaming head, at the same time the feeding mechanism is automatically controlled so as to be rendered ineffective when there is no filled can underneath the seaming head to be closed.

By means of the nuts 57 and 58 the position of the pusher may be adjusted relative to the slide rod 34, so that the can ends or covers will be moved forward the proper distance for seating the same underneath the seaming head. The oscillating lever 48 is connected to the sleeve 45 by a pin 47. This pin may be so constructed that if for any reason the pusher should be locked by the jamming of a cover, then the arm 46 will break the pin 47. In other words, the pin 47 will be sheared off by unusual strains so as to prevent the breaking of the parts of the machine.

While I have described in detail a mechanism which embodies my invention, it will be understood that changes in the details of construction and the arrangement of parts may be made without departing from the spirit of the invention, as set forth in the appended claims.

Having thus described my invention, what I claim is:

1. A can closing machine including in combination a can body support, a seaming head, means for giving the can body support and seaming head a relative movement for causing the seaming head to engage the can, a support for the can ends extending underneath the seaming head and held in fixed position relative thereto, said support for the can end having an opening therethrough, the center of which is in line with the seaming head, said support having means for centering the can end relative to said opening, a pusher for engaging the can end on the support and moving the same underneath the seaming head, and means for reciprocating said pusher, said reciprocating means for the pusher including devices which may be disconnected for rendering the feeding action of the pusher ineffective.

2. A can closing machine including in combination a can body support, a seaming head, means for giving the can body support and seaming head a relative movement for causing the seaming head to engage the can, a support for the can ends extending

underneath the seaming head and held in fixed position relative thereto, said support for the can end having an opening therethrough, the center of which is in line with the seaming head, said support having means for centering the can end relative to said opening, a pusher for engaging the can end on the support and moving the same underneath the seaming head, means for reciprocating said pusher, said reciprocating means for the pusher including devices which may be disconnected for rendering the feeding action of the pusher ineffective, and devices controlled by the can bodies fed to the closing machine for connecting said pusher to its reciprocating means.

3. A can closing machine including in combination a can body support, a seaming head, means for giving the can body support and seaming head a relative movement for causing the seaming head to engage the can, a support for the can ends extending underneath the seaming head and held in fixed position relative thereto, said support for the can end having an opening therethrough, the center of which is in line with the seaming head, said support having means for centering the can end relative to said opening, a pusher for engaging the can end on the support and moving the same underneath the seaming head, means for reciprocating said pusher, said reciprocating means for the pusher including devices which may be disconnected for rendering the feeding action of the pusher ineffective, and automatic means for disconnecting the pusher from its reciprocating means, said automatic means being controlled by the cans as they are fed to the closing machine for connecting said pusher to its reciprocating means.

4. A can closing machine including in combination a can body support, a seaming head, means for giving the seaming head and the can body support a movement relative to each other, a support for can ends held in fixed relation to the seaming head, a stack holder carried by the support for the can ends, a pusher for engaging a can end in the stack holder and moving the same underneath the seaming head, means operating in unison with the relative movements of the seaming head and the support for reciprocating the pusher, means for feeding can bodies underneath the seaming head, and means controlled by the can bodies as they are fed to the seaming head for connecting and disconnecting said pusher to and from its operating means.

5. A can closing machine including in combination a can body support, a seaming head, a support for the can ends, whereby said can ends may be held underneath the

seaming head, a pusher for engaging the can end and moving the same underneath the seaming head on said support, means for reciprocating said pusher, and means controlled by the filled cans for connecting and disconnecting said pusher to and from its operating means.

6. A can closing machine including in combination a can body support, a seaming head, a support for can ends held in fixed relation to the seaming head, means for feeding can bodies underneath the seaming head, a pusher for engaging a can end on said support and moving the same underneath the seaming head, means for reciprocating said pusher, and means controlled by the filled cans as they are fed to the seaming head for automatically connecting and disconnecting the pusher to and from its operating means.

7. A can closing machine including in combination a can body support, a seaming head, a support for can ends held in fixed relation to the seaming head, means for feeding can bodies underneath the seaming head, a stack holder carried by the support for the can ends, a pusher for engaging the can end in the stack and moving the same on said support beneath the seaming head, means for reciprocating said pusher, and means controlled by the filled cans as they are fed to the seaming head for connecting and disconnecting said pusher to and from its operating means.

8. A can closing machine including in combination a can body support, a seaming head, means for giving the seaming head and the can body support a movement relative to each other, a support for can ends held in fixed relation to the seaming head, means for feeding can bodies underneath the seaming head, a pusher for engaging the can ends on said support and moving the same underneath the seaming head, a slide rod connected to said pusher, a sleeve freely slideable on said rod, a latch for coupling said sleeve to the rod, and means for disconnecting the latch from the rod.

9. A can closing machine including in combination a can body support, a seaming head, means for giving the seaming head and the can body support a movement relative to each other, a support for can ends held in fixed relation to the seaming head, means for feeding can bodies underneath the seaming head, a pusher for engaging the can ends on the support and moving the same underneath the seaming head, a slide rod connected to said pusher, an oscillating lever, a sleeve on the rod connected to said oscillating lever, a latch for coupling the sleeve to the rod, a pin for locking said lever to the sleeve, said pin being so disposed as

to be broken by the movements of the lever upon a stopping of the movements of the pusher.

10. A can closing machine including in combination a can body support, a seaming head, means for giving the seaming head and can body support a movement relative to each other, a support for can ends held in fixed relation to the seaming head, means for feeding can bodies underneath the seaming head, a stack holder carried by said support for the can ends, a pusher for engaging a can end in the stack and moving the same underneath the seaming head, a reciprocating rod connected to said pusher, a sleeve freely slidable on said rod, a collar fixed to said rod, a latch carried by the sleeve and adapted to normally engage a locking lip on the collar, means for reciprocating the sleeve, a controlling plate carried by the support for the can ends, and movable relative thereto vertically, a cam carried by said controlling plate, for releasing the latch from the collar on the slide rod, a spring for normally depressing the plate to hold the cam in position for releasing the latch, said plate being so positioned that a filled can as it is moved to the seaming head will engage the plate and raise the same to move the cam out of the path of the latch.

11. A can closing machine including in combination, a can body support, a seaming head located above the said can body support, a support for can ends extending underneath the seaming head and held in fixed position relative thereto, said support for the can end having an opening therethrough, the center of which is in line with the seaming head, said support having means for centering the can ends relative to the opening, means for feeding the can ends on to the support at a point outside of the seaming head, devices for engaging the can end on the can end support and moving the same underneath the seaming head, means for reciprocating said devices, said reciprocating means including devices which may be disconnected for rendering the feeding action of said can end feeding devices ineffective, means controlled by the can bodies fed to the closing machine for connecting the can end feeding devices to the reciprocating means therefor.

12. A can closing machine including in combination a can body support, a seaming head, means for moving the seaming head and can body support relative to each other for causing the can to engage the seaming head, a can end support extending underneath the seaming head for holding and centering the can ends, a pusher for engaging the can ends and moving the same

along the can end support underneath the seaming head, means for reciprocating said pusher, said reciprocating means including a breakable pin connection whereby a blocking of the pusher will cause said pin to be severed, said reciprocating means also including means whereby the pusher may be connected or disconnected with its reciprocating means, and devices controlled by the can bodies fed to the closing machine for connecting said pusher to its reciprocating means.

13. A can closing machine including in combination a can body support, a seaming head, means for moving the seaming head and can body support relative to each other for causing the can body to engage the can end, and the can end and can body to engage the seaming head, a supporting plate extending underneath the seaming head and held in fixed relation thereto, said supporting plate having an opening therethrough, the center of which is in line with the seaming head, the lower face of said opening being cone-shaped for engaging and rounding up and centering the can body relative to the seaming head, a seat for the can end at the upper face of the opening for centering a can end relative to the seaming head, a stack holder carried by said support for feeding the can ends one at a time on to said support, a pusher reciprocating underneath the stack holder for engaging a can end and feeding the same along the support to the can end seat underneath the seaming head, and means for reciprocating said pusher including devices controlled by the filled cans fed underneath the seaming head whereby the pusher is moved forward to carry a can end on to its seat underneath the seaming head only when a can body is moved forward on to the can end support underneath the seaming head.

14. A can closing machine including in combination a can body support, a seaming head, means for moving the seaming head and can body support relative to each other for causing the can body to engage the can end, and the can end and can body to engage the seaming head, a supporting plate extending underneath the seaming head and held in fixed relation thereto, said supporting plate having an opening therethrough, the center of which is in line with the seaming head, the lower face of said opening being cone-shaped for engaging and rounding up and centering the can body relative to the seaming head, a seat for the can end at the upper face of the opening for centering a can end relative to the seaming head, a stack holder carried by said support for feeding the can ends one at a time on to said support, a pusher reciprocating under-

neath the stack holder for engaging a can end and feeding the same along the support to the can end seat underneath the seaming head, and means for reciprocating said pusher, said reciprocating means including devices for connecting and disconnecting the pusher with its actuating means, and means for operating said devices to automatically disconnect the pusher from its actuating means whereby said pusher is normally idle, said last named operating means being controlled by the filled cans as they

are fed underneath the seaming head for connecting the pusher to its actuating means, whereby a can end is fed underneath the seaming head at the same time a filled can is carried to the can body support.

In testimony whereof, I affix my signature, in the presence of two witnesses.

IVAR F. WARME.
